UNITED STATES PATENT OFFICE.

MATTHÄUS SCHLAGER, OF LINZ, AUSTRIA.

SCREW DRIVER.

Application filed September 6, 1923. Serial No. 661,812.

To all whom it may concern:

Be it known that I, MATTHÄUS SCHLAGER, a citizen of the Republic of Austria, residing at 3 Baumbachgasse, Linz, Austria, have invented new and useful Improvements in a Screw Driver, of which the following is a specification.

This invention relates to improvements in screw-drivers of the kind in which a screw-driver blade is adapted to be inserted in a slot provided in a second screw-driver blade, so that the two blades cross each other preferably at a right angle.

According to the present invention the screw-driver blade, adapted to be inserted in the slotted blade, is of a rhomboidal shape whereby, on fitting both blades together a firm cooperation between the two blades is automatically effected by the rhomboidal shape of the said blade.

One mode of carrying out the present invention is shown by way of example on the accompanying drawing, in which—

Fig. 1 is a plan view of one blade,

Fig. 2 a plan view of the other blade, and

Fig. 3 a side view of the blade illustrated in Fig. 2.

Fig. 4 shows the two blades fitted together to form the screw-driver according to the invention.

The screw-driver comprises two screw-driver blades or members, 1 and 2, provided at the ends with bits or knife-like edges preferably of different width with respect to one another. The blade 1 is provided with a slot 3 in the middle, through which the blade 2 of rhomboidal shape may be passed (Fig. 4). In this position the blades automatically interlock and cross each other, preferably at a right angle, and the blade which is not in use serves as a double-armed lever for turning the blade which is in use.

I claim:—

In a screw-driver the combination with a screw-driver blade provided at both ends with a bit and with a slot in the middle, of a rhomboid-shaped screw-driver blade provided at both ends with a bit and adapted to be passed through the said slot whereby a firm cooperation between the two blades is effected by the rhomboidal shape of the blade last mentioned.

In testimony whereof I have signed my name to this specification.

MATTHÄUS SCHLAGER.
